CONDUIT BENDER

Harry Blythe, Denver, Colo.

Application June 30, 1949, Serial No. 102,379

4 Claims. (Cl. 153—40)

1

This invention relates to a conduit bender, and has for its principal object the provision of a simple and highly efficient device which can be preset for producing bends of any desired degree in both pipe and thin-walled conduit or tubing of various diameters.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved bender; Fig. 2 is a side view thereof;

Fig. 3 is an enlarged end view of the bending portion of the bender;

Fig. 4 is a detail, perspective view of a pipe clamp employed in the improved bender;

Fig. 5 is a fragmentary detail section, taken on the line 5—5, Fig. 3.

Fig. 6 is a similar section, taken on the line 6—6, Fig. 3;

Fig. 7 is a horizontal cross-section, taken on the line 7—7, Fig. 5;

Fig. 8 is an enlarged, fragmentary section, taken on the line 8—8, Fig. 5;

Fig. 9 is a detail section taken on the line 9—9, Fig. 6;

Fig. 10 is a developed section, taken on the line 10—10, Fig. 6, illustrating the bending sector in the closed position for bending tubing; and

Fig. 11 is a similar section, illustrating the bending sector in the expanded pipe or conduit bending position.

The improved bender is mounted on a supporting frame consisting of two inverted, U-shaped side leg members 13 preferably formed from metal pipe and joined by means of cross frame members 14 welded or otherwise secured therebetween. The cross members 14 support two longitudinally extending, parallel roller guides 15 between which a pair of flat rollers 16 and a double groove roller 17 extend, for receiving the pipe or tubing to be bent.

A vertical side plate 18 is welded to one of the leg supports 13 and extends upwardly therefrom. A channel guide track 19 is secured to each vertical edge of the plate 18 and acts to hold a slide plate 20 in place thereon. The slide plate is vertically movable and may be adjusted in any de-

2

sired vertical position by means of a jack screw 21. The screw 21 is threaded through a foot member 22 mounted on a leg 23 extending downwardly from the side plate 20 and is supported and rotatably mounted in a foot flange formed on the side plate 18 and in one of the cross members 14.

A tubular spindle 24 is fixedly mounted in the slide plate 20 and extends horizontally outward therefrom to support a bearing collar 25 formed on a bending sector member 26. The vertical position of the slide plate 20 can be determined from an index pointer 27 which indicates positions on a scale 28 on one of the track channels 19.

The bending sector sleeve 25 is provided with a handle socket 29 for receiving a suitable lever handle 30 which is locked in place in the socket 29 by means of a set screw 31. The bending sector is provided with a clamp-supporting arm 32 extending radially downward and sideward from the sector 26.

A swinging pipe-clamping member 33 is mounted on a hinge pin 34 at the bottom of the arm 32 and is provided at its top with a hook 35 which can be hooked over a projecting lug on the upper portion of the arm 32. The clamp 33 is provided with two pipe-engaging notches, a large diameter notch 36 and a small diameter notch 37.

The sector member 26 terminates at its peripheral edge in a groove which forms one-half of a large diameter pipe-receiving groove 38. The other half of the groove 38 is formed by means of a side arc member 39 which is attached to the sector member 26 by means of suitable attachment screws 40 which extend through the sector member 26 and are threaded into the side arc member 39. The outer face of the sector 26 is formed with an arcuate curved shoulder 61 which forms one-half of a small diameter pipe-receiving groove 41. The other half of the groove 41 is formed by means of an arcuate side plate 42 which is attached to the sector member 26 by means of suitable attachment screws 43 which extend through the side plate 42 and are threaded into the sector member 26. The tangential axes of the grooves 38 and 41 align with the axes of the notches 36 and 37 in the clamp 33 and with the grooves in the grooved roller 17.

The screws 40 extend through slotted screw holes 44 in the sector member 26, and the screws 43 extend through similarly slotted screw holes 45 in the side plate 42. This allows the side arc member 39 and the arcuate side plate 42 to be

shifted circumferentially. The purpose of this circumferential shift is to vary the width of the grooves 38 and 41. This is accomplished by forming raised lugs 46 on the sector member 26 which fit into receiving notches 47 on the side arc member 39 and the side plate 42. When the lugs 46 are in the notches 47 the grooves 38 and 41 are of minimum width. This width can be increased a predetermined amount by loosening the screws 40 and 43 and slipping the arc member 39 and the side plate 42 circumferentially so that the lugs 46 will rest on the surface of the sector member 26 and not in the notches 47, as shown in Fig. 11.

The sector sleeve 25 is held in place on the spindle 24 by means of a latch pin 48 which is projected outwardly from the spindle by means of a latch spring 49, and which can be pressed inwardly to remove the sleeve 25 by means of a finger tab 50.

The forward swing of the handle 30 is limited by means of a stop angle 51 on the leg 23 which is contacted by the arm 32. The rearward swing of the handle 30 can be preset to four different stopping positions by means of four stop screws 52 projecting outwardly from the sides of a rectangular turret block 53 which is attached to the slide plate 29 by means of a pivot screw 54. The turret block can be temporarily latched in any of its four positions by means of a latch spring 55 which selectively engages any one of four receiving notches 56 in the back of the turret block 53, as shown in Fig. 8. The head of the uppermost stop screw 52 is in the path of, and is contacted by, a lug 57 formed on and projecting from the handle socket 29.

The bender can, of course, be designed to handle two differing sizes of pipe or conduit of any desired diameter. The usual bender is designed to handle $\frac{3}{4}$ inch and $\frac{1}{2}$ inch pipe or tubing. A different sector member can be slipped in place on the spindle, however, for handling other sizes.

Operation

Let us assume that the $\frac{1}{2}$ inch and $\frac{3}{4}$ inch sector is in place and that it is desired to bend $\frac{3}{4}$ inch tubing to a 90° arc. The crank 58 is rotated to position the pointer 27 opposite the 90° bend mark on the index 28. The tubing is inserted over the rollers 16 and 17 to bring the start of the bend below the axis of the spindle 24. The turret block 53 is rotated to position the proper screw 52 upwardly for a $\frac{3}{4}$ inch tubing bend. The clamp 33 is swung into place beneath the tubing and the handle 30 is pulled rearwardly as far as possible. This brings the lug 57 against the uppermost stop screw 52, producing a perfect 90° bend in the tubing.

Should a 90° bend be desired in $\frac{1}{2}$ inch tubing, it is placed in the groove of the roller 17 below the small groove 41 and the settings are made at the pointer 27 and at the rotating turret head 53 to suit $\frac{1}{2}$ inch tubing. The handle 30 is then rotated rearwardly as far as possible.

For bending pipe it is necessary that the grooves 38 and 41 be widened, since the outside diameter of pipe exceeds the outside diameter of tubing. This is done as before described by loosening the screws 40 and 43 and slipping the arc member 39 and the side plate 42 circumferentially so that they will rest on their lugs 46 to produce a widened groove, as shown at the groove 41 in Fig. 9. The settings at 27 and 53 are then properly made to accommodate pipe bends.

A scale is furnished with each machine, telling

the operator the proper settings of the turret head 53 and the pointer 27 for any desired pipe or tubing. A second pointer 59 is mounted over an index 60 on the sleeve 25 to give the desired degrees for bends less than 90° .

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. In a pipe bender having a rotary sector member provided with an arcuate pipe-receiving groove for forming a bend in a pipe, means for varying the width of the groove in said sector member to adapt said groove to either pipe or tubing, comprising: a half groove formed in said sector member; an arcuate side plate, the other half groove being formed in said side plate; screws attaching said side plate to said sector member; projections on said sector member; and complementary receiving depressions in said side plate for receiving said projections, said screws being positioned in slotted screw holes so that said side plate may be shifted circumferentially to place said projections either in or out of said depressions.

2. A pipe bending sector for pipe bending devices comprising: a bending sector having an arcuate edge; a transversally curvated groove in said edge forming one-half of a 180° groove; a side arc member corresponding in radius to said sector and having a similarly curvated arcuate edge forming the other half of a 180° groove, said side arc member being circumferentially shiftable relative to said sector; and means acting to separate said arc member from said sector in consequence of the relative circumferential movement therebetween.

3. A pipe bending sector for pipe bending devices comprising: a bending sector having an arcuate edge; a transversally curvated groove in said edge forming one-half of a 180° groove; a side arc member corresponding in radius to said sector and having a similarly curvated arcuate edge forming the other half of a 180° groove, said side arc member being circumferentially shiftable relative to said sector; and threaded members securing said arc member against said sector, said threaded members extending through arcuately elongated openings to allow said arc member to be shifted circumferentially, the contacting surfaces between said arc member and said sector being such that the two will be spaced further apart at one circumferential position than another.

4. A pipe bending sector for pipe bending devices comprising: a bending sector having an arcuate edge; a transversally curvated groove in said edge forming one-half of a 180° groove; a side arc member corresponding in radius to said sector and having a similarly curvated arcuate edge forming the other half of a 180° groove, said side arc member being circumferentially shiftable relative to said sector; means acting to separate said arc member from said sector in consequence of the relative circumferential movement therebetween; an arcuate shoulder of less radius than said sector projecting concentrically from one face thereof, a transversally arcuate groove in said shoulder forming one-half of a second 180° groove; an arcuate side plate having the remainder of said latter groove secured against said sector below said shoulder; and

means for varying the spacing between said sector and said arcuate side plate.
